 Dearborn, Mich.

Application August 10, 1950, Serial No. 178,674

2 Claims. (Cl. 201—51)

1

This invention relates to rheostatic switches and in particular to improvements in powdered carbon type rheostatic switches.

The primary object of the invention is to provide an improved powdered carbon type variable rheostatic switch which is accurate and sensitive, which will not become ineffective through repeated use, which maintains constant resistance at any given point of travel of the movable element, and which maintains uniformity of its variable resistance at all points during both its make and break operation.

Another object of the invention is to provide a rheostatic switch of the class described which has an extremely long life, requires no servicing, which can be operated manually, mechanically or thermostatically, which is inexpensive to manufacture, and which is adaptable to many uses wherein rheostatic control or combined rheostatic and off and on control of circuits is desirable or required.

Other objects of the invention will become apparent by reference to the following detailed description taken in connection with the accompanying drawing, in which:

Fig. 1 is a vertical sectional view through a rheostatic switch embodying the invention.

Fig. 2 is a horizontal sectional view taken on the line 2—2 of Fig. 1.

Fig. 3 is a vertical sectional view similar to Fig. 1 showing an alternate embodiment of the invention.

Fig. 4 is a horizontal sectional view taken on the line 4—4 of Fig. 3.

Fig. 5 is a view part in section and part in elevation showing the resilient compressible cylinder employed in the embodiment of the invention disclosed in Figs. 1 and 2.

Fig. 6 is a view part in section and part in elevation showing the resilient compressible cylinder employed in the embodiment of the invention described in Figs. 3 and 4.

Referring now to the drawings wherein like numerals refer to like and corresponding parts throughout the several views, the particular embodiment of the invention disclosed in Figs. 1, 2 and 5 comprises, in general, a cylindrical capsule 10 closed at its bottom end 100 and open at its top end, a resilient compressible cylinder 11 preferably formed of rubber, silicon rubber or other material or combination of materials which is heat resistant, nonconductive and yet will spring back to its normal size and shape after axial compression, the said cylinder 11 having a central axial aperture 12 therethrough

preferably smaller at the lower end 120 thereof and is provided with inner circumferential grooves 13 and 14 near the top and bottom thereof extending radially outward from the said central axial aperture 12, a movable contact 15 and fixed contact 16 positioned in the said inner circumferential grooves 13 and 14, the said movable contact 15 comprising a disc 150 positioned in the upper inner circumferential groove 13, a central elongated tapered contact point 151 and a contact head 152, the said fixed contact 16 comprising a disc 160 positioned in the lower inner circumferential groove 14 and a contact head 161 extending through the lower end 120 of the axial aperture 12 of the cylinder 11 into contact with the bottom end 100 of the capsule 10, and powdered or finely ground carbon 17 disposed in the axial aperture 12 of the cylinder 11 between the discs 150 and 160 of the movable and fixed contacts 15 and 16 respectively.

20 A piston 18 or some other suitable means is employed for manually, mechanically or thermally compressing the resilient cylinder 11 in the direction indicated by the arrow 20 and moving the movable contact 15 toward and into contact with the fixed contact 16 with the contact point 151 of the movable contact 15 in engagement with the fixed contact 16.

25 In the illustrative embodiment shown in Figs. 1, 2 and 5, the piston 18 contacts the contact head 152 of the movable contact 15 as well as a fiber or other washer 19 disposed around the said contact head 152 of the movable contact 15. This construction assures uniform compression and movement of the resilient cylinder 11 and the movable contact 15 within the capsule 10 responsive to movement of the piston 18 in the direction illustrated by the arrow 20. When pressure on the piston 18 moving it in the direction indicated by the arrow 20 is released, the resilient compressible cylinder 11 returns itself and the piston 18 to their normal position assumed prior to the application of pressure on the piston 18. A lead 21 connected to the piston 18 provides an electrical connection to the movable contact 15 through the said piston 18. A lead 22 connected to the capsule 10 provides an electrical connection to the fixed contact 16 through the said capsule 10.

30 40 45 50 55 When a rheostatic switch embodying the invention is connected in an electric circuit, and the movable contact 15 is in its normal position as shown in Fig. 1, the resistance between the movable and fixed contacts 15 and 16 is so great that practically no current passes through the

powdered or finely ground carbon 17. As the piston 18 compresses the resilient compressible cylinder 11, the movable contact 15 moves toward the fixed contact 16 compacting the powdered or finely ground carbon 17 while the elongated tapered contact point 151 of the movable contact 15 approaches the fixed contact 16, and the resistance between the movable and fixed contacts is progressively lessened whereby the current passing through the powdered or finely ground carbon 17 progressively increases until, when the pointed end of the tapered contact point 151 of the movable contact 15 contacts the fixed contact 16, substantially full current is passing through the powdered or finely ground carbon 17 thereby eliminating any arcing of the contacts 15 and 16 during the make and break thereof.

Upon release of the piston 18, the resilient compressible cylinder 11 progressively returns from its compressed position to its normal position shown in Fig. 1 with a corresponding progressive decrease in current passing between the contacts 15 and 16. The slight roughness of the inside surface 23 in the resilient compressible cylinder 11 as indicated in Fig. 5 causes a movement of the granules of the carbon 17 during axial movement of the resilient cylinder 11 whereby to prevent fixation of permanent caking of the carbon granules. This assures the granules of the carbon 17 following the tapered point 150 of the movable contact 15 and a constant resistance at any given point in the movement of the movable contact 15.

The embodiment of the invention disclosed in Figs. 3, 4 and 6 is like and similar to the embodiment of the invention disclosed in Figs. 1, 2 and 5 except that the inside surface of the resilient compressible cylinder 11 is provided with a plurality of radially disposed circumferential grooves 230 creating a very rough or ribbed inside surface in the resilient compressible cylinder 11 which causes a greater and more positive movement of the granules of the carbon 17 by mechanically activating the same whereby to prevent fixation or permanent caking thereof by causing the carbon granules to "work" during the movement of the tapered point 150 of the contact 15 thereinto and therefrom.

The proportioning of the tapered point 150 of the contact 15 with respect to the volume and fineness of the granules of the carbon 17, and the distance between the movable contact 15 and the fixed contact 16 determines the characteristics of rheostatic switches embodying the invention. The size of the rheostat and volume and fineness of carbon granules employed dictates the extent to which the inner surface of the compressible cylinder 11 is roughened or otherwise deformed.

Although but a single embodiment of the invention and one modification thereof have been disclosed and described in detail, it is obvious that many changes may be made in the size,

shape, arrangement and detail of the elements of the invention and the proportioning thereof without departing from the spirit and scope thereof as defined by the appended claims.

I claim:

1. A rheostatic switch comprising a capsule, a resilient compressible element having an aperture axially therethrough disposed in the said capsule, a pair of contacts disposed in axial spaced relationship in said resilient compressible element, one of said contacts including an axially tapered contact point disposed toward the other contact whereby to contact the same when the said resilient compressible element is axially compressed, and finely ground carbon disposed in the said axially disposed aperture in the resilient compressible element between the said contacts, the inner surface of the said resilient compressible element at the axial bore therethrough between the said contacts being provided with a plurality of deformations between the said contacts whereby to mechanically engage and activate and cause turbulence in the said carbon granules and prevent caking thereof during axial compression and expansion of the said resilient compressible element.
2. In a rheostatic switch, a resilient compressible element having an aperture axially therethrough, the said compressible element having a pair of axially spaced circumferentially disposed grooves therein communicating with the said axial aperture therethrough, a pair of contacts disposed in said axial spaced grooves in said resilient compressible element, one of said contacts including an axially tapered contact point disposed toward the other contact whereby to contact the same when the said resilient compressible element is axially compressed, and finely ground carbon disposed in the said axially disposed aperture in the resilient compressible element between the said contacts, the inner surface of the said resilient compressible element at the axial bore therethrough between the said contacts being circumferentially ribbed whereby to mechanically engage and activate and cause turbulence in the said carbon granules and prevent caking thereof during axial compression and expansion of the said resilient compressible element.
